UNITED STATES PATENT OFFICE

147,861

DESIGN FOR A SPEAKER UNIT CABINET

Nels A. Miller, Oak Park, Ill., assignor to J. P. Seeburg Corporation, Chicago, Ill., a corporation of Illinois

Application May 4, 1946, Serial No. 129,326

Term of patent 14 years

(Cl. D26—14)

To all whom it may concern:

Be it known that I, Nels A. Miller, citizen of the United States and resident of Oak Park, in the county of Cook and State of Illinois, have invented a new, original, and ornamental Design for a Speaker Unit Cabinet, of which the following is a specification, reference being had to the accompanying drawing, forming part thereof.

I claim:

The ornamental design for a speaker unit cabinet, as shown.

NELS A. MILLER.
